DESIGN FOR A CAP

Helen C. Cookman, New York, N. Y.

Application March 9, 1943, Serial No. 109,704

Term of patent 7 years

To all whom it may concern:

Be it known that I, Helen S. Cookman, a citizen of the United States, residing at New York, county of New York, and State of New York, have invented a new, original, and ornamental Design for a Cap, of which the following is a specification, reference being had to the accompanying drawings, forming part thereof.

Fig. 2 is a back view of the same.

Fig. 3 is a side elevational view of the same.

Fig. 4 is a top view of the same.

I claim:

The ornamental design for a cap, as shown.

HELEN C. COOKMAN.
